[57] CLAIM

The ornamental design for a retractable roller directory, as shown and described.

DESCRIPTION

FIG. 1 is a front elevational view of a retractable roller directory showing my new design;

FIG. 2 is a top plan view thereof;

FIG. 3 is a bottom plan view thereof;

FIG. 4 is a back elevational view thereof;

FIG. 5 is a left end elevational view thereof, both ends being identical;

FIG. 6 is a front elevational view of a second embodiment thereof;

FIG. 7 is a left end elevational view of the embodiment of FIG. 6, the top, bottom and back views being substantially identical to FIGS. 2, 3 and 4 respectively;

FIG. 2

FIG. 5

FIG. 1

FIG. 3

FIG. 4

FIG. 7

FIG. 6
